DESIGN FOR A DRESS

Nat Abelson, New York, N. Y.

Application August 19, 1937, Serial No. 71,196

Term of patent 3½ years

To all whom it may concern:

Be it known that I, Nat Abelson, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the dress disclosed of the specific rhinestone trim at the neckline and on the pockets as shown.

I claim:

The ornamental design for a dress substantially as shown and described.

NAT ABELSON.
